UNITED STATES PATENT OFFICE

JOSEPH L. CHANTEMERLE, OF NEW YORK, N. Y., ASSIGNOR, BY MESNE ASSIGNMENTS, TO SPERRY GYROSCOPE COMPANY, INC., OF BROOKLYN, NEW YORK, A CORPORATION OF NEW YORK

GYROCOMPASS TRANSMISSION SYSTEM

Application filed June 16, 1926. Serial No. 116,271.

This invention relates to transmission systems for gyroscopic compasses. It is one object of this invention to provide means whereby both a fine and a coarse indication of the 5 master compass reading may be transmitted to the repeater compasses. This construction is applicable to both a D. C. and an A. C. system of transmission and is of great 10 importance where a synchronous transmission system is desired, that is, one in which the repeater instrument cannot get out of step with the master instrument even though the master instrument be turned relative to the repeater when the current is off and later 15 reestablished. For this purpose there is usually employed a 1:1 transmission system, since in any system of multiplication of movement, that is, where the transmitter operates a plurality of revolutions for each 20 revolution of the master, it is possible for the repeating instrument to lose step with the master should the master be turned through an angle greater than one revolution of the transmitter when the current is off. 25 A 1:1 transmission system, however, means that the transmitter, as well as the repeating instrument index, moves through but one revolution for each revolution of the master instrument, resulting in an index which can 30 be read accurately only to within one or two degrees. By my invention, however, I provide, in addition to this coarse or 1:1 transmitter, a fine transmitter geared to the master instrument through multiplication gearing 35 so that the said fine transmitter operates through a plurality of revolutions for each revolution of the master instrument. By causing the fine transmitter to control an auxiliary repeating instrument, the said 40 auxiliary instrument acts as a vernier for the main repeating instrument and enables fine readings to within, say, 10 minutes of arc to be read, while at the same time permitting 45 the system to remain self-synchronous.

It is a further object of my invention to provide a system of fine and coarse transmission wherein usual compass corrections 50 may be introduced into said transmission system so that both the coarse and fine transmitters will transmit corrected readings.

For this purpose I may employ means whereby corrections are introduced into the coarse and fine transmitters in the same ratio as said transmitters bear to each other.

A further object of the invention is the 55 provision of an A. C. system of transmission between a master compass and one or more repeater compasses.

A further object of the invention is the 60 provision of both a fine and a coarse A. C. transmission system between a master compass and one or more repeater compasses.

Still further objects and advantages of 65 my invention will become apparent in the following detailed description thereof.

In the accompanying drawings

Fig. 1 is a front elevation, partly sectioned 70 vertically and with parts removed, showing a master gyroscopic compass having my invention applied thereto.

Fig. 2 is a plan view of the master compass of Fig. 1.

Fig. 3 is a section taken substantially on 75 the line 3-3 of Fig. 4 and disclosing a lost-motion drive between the master compass and a transmitter.

Fig. 4 is a section taken substantially on 80 the line 4-4 of Fig. 3.

Fig. 5 is an enlarged detailed plan view of 85 the mechanism for introducing corrections into the transmitters.

Fig. 6 is a vertical section through the coarse transmitter and the correcting mechanism taken substantially on the line 6-6 of 90 Fig. 5.

Fig. 7 is a section taken substantially on 95 the line 7-7 of Fig. 5.

Fig. 8 is an enlarged vertical section through one of the pivot blocks of Fig. 7.

Fig. 9 is a wiring diagram of the transmitters and repeaters.

Referring to Fig. 1 of the drawings, there will be seen that I have illustrated my invention as applied to a gyroscopic compass system, comprising the gyro casing 10 in which operates the gyroscopic rotor, said casing being mounted on horizontal axes in the vertical ring 11, said casing and ring constituting the sensitive element which is suspended 100 from the spider 12 by any suitable suspension

for movement about a vertical axis, as for example, by the magnetic suspension 13. Rotatably supported by said spider 12 is the usual follow-up element 14 carrying the 5 azimuth gear 15 meshing with a pinion 16 of an azimuth motor 17. The mercury ballistic element 18 and eccentric pivot 19 are also disclosed. In accordance with the ordinary 10 method of operation of the gyroscopic compass, the azimuth motor causes the follow-up element 14 to follow the apparent movements of the sensitive element and said movements of the follow-up element have heretofore been indicated by a compass card carried by 15 said follow-up element. Such a card may be provided here but since I illustrate my invention in connection with a synchronous transmission system wherein the transmitter has a 1:1 relation with the master compass, I 20 may mount the card C on the armature of the said transmitter T (see Fig. 2).

For synchronous transmission of the movements of the master compass to the repeaters, I may employ the said transmitter T geared 25 by gearing 21-22 to the follow-up element, the said gearing having a 1:1 relation. Although the said transmission system may be a D. C. transmission system, I have illustrated my invention in connection with an A. C. 30 transmission system. The transmitter T, therefore, will comprise field poles and an armature, the said armature being rotated by the follow-up element, and the displacement of the armature relative to the field poles being transmitted to a similar receiver M having similar field poles and armature to cause said receiving instruments to repeat the movements of the transmitter T. It will be understood that if a D. C. transmission system is employed, said transmission system 35 may be as shown in the patent to Elmer A. Sperry #1,255,480, dated February 5, 1918, as shown in Fig. 6 thereof, except that the transmitter would have a 1:1 relation with 40 the follow-up element instead of rotating a plurality of times for each revolution of the master compass.

I have shown a compass card C mounted on the shaft of the armature of transmitter 45 T and it will be apparent that since said card C is sub-divided into 360 degrees, as shown in Fig. 2, accurate readings to within say 5 or 10 minutes of arc is impossible and at best the readings can be taken accurately 50 only to within say the nearest degree. At the same time, therefore, that I operate the 1:1 transmitter T, which I shall hereafter call the coarse transmitter, I operate also a fine transmitter T' having a multiplying 55 gearing connection 16' to the azimuth gear 15, so that said fine transmitter T' makes a plurality of revolutions, in this case thirty-six, for each revolution of the master compass. A complete revolution of the card C' 60 of transmitter T', therefore, corresponds to

but 10° of arc and permits reading to within 5 or 10 minutes of arc. The employment of the fine transmitter T' does not destroy the complete synchronization of the transmission system, for should the master compass be 70 turned through, say, 15° when the current is off, upon reestablishment of the current, repeater motor M will take up a position in exact synchronization with the transmitter T and, therefore, with the master compass, 75 that is, it will be moved through the entire 15° while repeater motor M' will move through the remaining 5° so that the absolute synchronization of the system is at no time destroyed, and at the same time I am enabled 80 to transmit very fine readings of the compass movements.

I have further devised a system for introducing the necessary corrections which must be introduced in the repeater instruments and also preferably in the master compass cards to 85 compensate for various errors that necessarily arise due to the movements of the ship or other dirigible craft on which the compass is mounted. The complete theory underlying said errors is set forth in the said Sperry patent wherein it is shown that whenever a vessel, on which the compass is mounted, has a meridional course component, an error is 90 set up which is proportional to the speed of the ship, the latitude and the course of the ship. The total error arising from this cause is set forth in the equation

$$D = \frac{aK \cos H}{\cos L} + b \tan L$$

100

in which D is the total correction, a and b are constants, K is the linear speed of the ship in knots, H is the angle in degrees of ship's heading or course from the true geographical north, and L is the latitude. From this it will be seen that there are two types of corrections to be introduced. One is a correction which is a function of the course and must, therefore, be constantly controlled by the course that is being traveled, while the other is an additive quantity which, for any given latitude, need be applied but once. In the said Sperry patent these corrections were introduced by the mechanism disclosed in Fig. 4 thereof which shifted the rubber line cooperating with the master compass card. In my invention I introduce said corrections as follows:

Since my transmitters are of the A. C. type, I may introduce a correction by varying the movement of the armature, or preferably, since the armature is geared to the compass, by moving the field poles which are ordinarily stationary. Thus, as shown in Fig. 6, the field poles may be operated by actuating gears 30, 30' fixed to the casing carrying the said poles of the respective transmitters, said gears being controlled by the correcting mechanism in the manner hereinafter de-

105

110

115

120

125

130

135

140

scribed. Any relative change of position between the armature and the field poles will, of course, transmit a change to the receiving instruments, M, M', that is to say, the corrected 5 readings will thus be transmitted to the receiving instruments. By mounting the rubber ring L for movement with the field poles, as shown in Fig. 6, I introduce the correction by varying the position of the rubber line as was 10 heretofore done in the said Sperry patent cited, for instance.

Since the two transmitters T-T' are independent of each other, each of these must be corrected and the fine transmitter T' must 15 have the correction multiplied in the same degree as the movement of its dial C' is multiplied over that of dial C. Thus, for example, in the illustration, card C' moves 36 times as rapidly as card C and, therefore, whatever 20 correction is introduced in transmitter T must be introduced also in transmitter T' and multiplied 36 times. Preferably I employ a single means for controlling both connections, said means taking the form of a gear 25 32 at the end of a pivoted segment 33 and said gear being suitably geared through idlers 70 and 70' to the pinions 30, 30' fixed to move with the field poles of the respective transmitters. The ratio of gearing is such that 30 the correction introduced in the field poles of transmitter T' is multiplied 36 times with respect to the movement of the field poles of transmitter T. Not only, therefore, am I enabled by this means to transmit both fine 35 and coarse indications, but I am enabled to transmit corrected fine and coarse indications.

It will be understood that if a D. C. system 40 of transmission is employed, the same method of introducing the correction may be employed, that is, a single gear, suitably geared to the armature or trolleys contacting therewith in the form shown, for instance, in the said Sperry patent, or in a patent to H. L. 45 Tanner No. 1,412,760, dated April 11, 1922 for correction device for gyroscopic compasses, to move the armature and contacts relatively. As previously stated at least one of said armatures would have a 1:1 relationship with 50 the movements of the master compass.

It will now be seen from the equation set forth hereinbefore that there are two corrections to be introduced, one of which is an additive quantity which, in any given latitude, 55 may be made in a single operation and the other of which is a continuing correction which is a function of the course, being traveled and must, therefore, be at all times tied up with the compass so that it may vary as the 60 course varies.

For introducing the first correction, that is, the additive correction, I may merely shift the gear 32 at the end of the segment 33 by any suitable adjusting means like that shown 65 in Fig. 2, comprising an adjusting screw 34

operating in a fixed bracket 35 and threaded into the gear 32 slidably mounted on segment 33. This will at once introduce the correction in the two transmitters in the proper ratios and the said corrections will be transmitted to the repeating instruments. This correction is not used in some types of compasses and may be omitted where not needed without affecting the operation of my invention. 70

For introducing the second correction I may provide means for suitably controlling the movements of said segment and its attached gear from the master compass. For this purpose I may provide upon the follow-up element driven from the master compass a so-called cosine ring 40, that is, a ring having either a cam slot, or as shown an eccentric groove 41 within a circular member, which is so designed that its eccentricity from point to point varies in a predetermined degree in accordance with the function of the ship's heading. The eccentricity of said cosine ring transmits its movements through a suitable linkage such as the bell crank 44 and lever 45 to the segment. The connection between said lever and said segment is such that another factor of this correction, namely, the speed and latitude may also be introduced to effect the movement of the segment. For this purpose the lever is shown in the form of a fork pivoted within a support 42 at 43 and within said fork slides a pivot 46 (shown enlarged in Fig. 8) forming the pivotal connection between the segment 33 and the lever 45. It will be seen that when the two pivots 43 and 46 are in alignment, rotation of the lever 45 causes no movement of the segment 33. The slideable pivot 46 is moved within grooves 47 by means of an adjusting nut 50 mounted on threaded stem 50' which is threaded through a boss 80 of segment 33 and which is rotatably but nonslidably mounted at its inner end in the pivotal connection 46. Said stem also carries a vertical scale 51 graduated in degrees of latitude and which is readable upon a scale 51 graduated in accordance with speed in knots. The curves on the plate 51 are so plotted that when the indicated latitude intersects the curve for the indicated speed, the pivotal connection 46 will be shifted in accordance with the required combined functions of both speed and latitude. The lever arm between the two pivots is thus varied so that any movement of the lever 45 will thus transmit a greater or lesser movement to the segment which is pivoted at 49 within support 42. The final movement of the segment, therefore, is the 100 component of the course as determined by the cosine cam slot 41 and bell crank 44, aid of the speed and latitude, as determined by the position of the slideable pivot 46. These corrections are introduced into the transmitters through the same gearing 32 as the additive 105

110

115

120

125

130

latitude correction was introduced so that this correction also is suitably multiplied in the fine transmitter T.

Since the follow-up element is usually given a continuous small oscillatory movement, known as the "hunt", in order to overcome static friction, means may be provided herein for eliminating this movement from the transmitters. For this purpose the gears 19 which are driven by the azimuth gear 22 are not connected directly to the respective armature shafts, as for example, shaft 60 in Fig. 1, but said gears are connected to said armature shaft through a hunt eliminating or lost motion device indicated generally at 61. Thus, for example, in Fig. 1 the gear 21 is connected to its armature shaft 60 through the hunt eliminating device 61 shown in detail in Figs. 3 and 4. Gear 21 is fixed to a 20 shaft 62 which carries a member 63 thereon, said member being adapted to engage one or the other of members 64 fixed to a casing 65 which is fixed to the armature shaft 60. The member 63 is of such size and the space between the members 64 is such that said member 63 engages one or the other of said members 64 depending upon the direction of rotation of shaft 62 only at a certain degree of lost motion. This degree of lost motion is 25 equivalent to the amount of movement which would ordinarily be transmitted by the hunting movement of the compass and is, therefore, much larger on the fine than on the coarse transmitter. The degree of lost motion may be varied by any suitable adjusting means which will move members 64 toward or away from member 63 to reduce the increasing space between said member 63 and said members 64. For this purpose I have 30 shown in Fig. 3 a pinion 67 engaging with the outer threaded periphery 68 of members 64 to effect the necessary adjustment of said members 64.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In combination, a gyroscopic compass, means for transmitting the indications of said compass including coarse and fine transmitters having a predetermined ratio of

movement with respect to said compass and to each other, means whereby said compass actuates said transmitters, a correction device also actuated from said compass, and means for introducing corrections from said device into each of said transmitters in the same ratio as said first ratio of movement. 70

2. In combination, a gyroscopic compass subject to hunting movements, means for transmitting the indications of said compass including coarse and fine transmitters having a predetermined ratio of movement with respect to said compass and to each other, means whereby said compass actuates said transmitters, including a pair of lost motion devices for eliminating said hunting movement and means for introducing corrections into said transmitters simultaneously in the same ratio as said first ratio of movement. 75

3. In combination, a gyroscopic compass adapted to be mounted on a craft, means for transmitting the indications of said compass including coarse and fine transmitters having a predetermined ratio of movement with respect to said compass and to each other, means whereby said compass actuates said transmitters, and means for introducing corrections into said transmitters in the same ratio as said first ratio of movement, comprising a member shifted by movements of the compass, means whereby said member is adjusted to correct also for speed, and latitude of said craft and gearing of different ratios connecting said member and each 90 transmitter. 95

4. In combination, a gyroscopic compass, means for transmitting indications of said compass including coarse and fine transmitters having a predetermined ratio of movement with respect to said compass and to each other, a follow-up element, means whereby said element actuates said transmitters, and means including a common operating member governed in part by said element and gearing between said member and said transmitters for introducing corrections into said transmitters in the same ratio as said first ratio of movement. 100 105

5. In a gyroscopic compass adapted to be mounted on a dirigible craft, an A. C. transmission system including a plurality of transmitters and repeaters each transmitter having an armature and a stator, means whereby said compass actuates the armatures of said transmitters at a predetermined ratio of movement relative to each other, a card carried by each armature, a lubber's line on each stator on which each card is read and means also actuated in part from said compass for shifting the stators of said transmitters and the said lubber lines in the same ratio for introducing corrections. 110 115

6. In a gyroscopic compass adapted to be mounted on a dirigible craft, an A. C. trans- 120 125

- mission system; including a plurality of transmitters and repeaters each transmitter having an armature and a stator, means whereby said compass actuates the armatures 5 of said transmitters at a predetermined ratio of movement relative to each other, a card carried by each armature, a rubber's line on each stator on which each card is read and means including a single member, and gearing 10 connections between said member and the stators of said transmitters for shifting said stator and the attached rubber lines in the same ratio for introducing corrections.
7. In a gyro-compass, the combination with 15 a follow-up element of the compass, of a plurality of transmitters driven therefrom at different gear ratios, a correction device for said transmitters, comprising a member rotated in accordance with a function of the 20 position of said element, means settable in accordance with speed and latitude varying the drive between said member and element, and gearing of different gear ratios connecting said member and each of said transmitters.
8. In a gyroscopic compass, a direction responsive element, a coarse transmitter and a fine transmitter actuated by said element, a 360° coarse compass card carried by the 25 coarse transmitter and a 10° vernier card carried by the fine transmitter.
9. In a gyro compass, the combination with the follow-up element of the compass, of a plurality of transmitters driven therefrom 30
- 35
- 40
- 45
- 50
- 55
- 60
- 65

- at different gear ratios, a correction device for said transmitters, comprising a member rotated in accordance with a function of the position of said element, means settable in accordance with speed and latitude varying the drive between said member and element, separate means settable in accordance with another function of latitude for adding an additional corrective movement to said member, and gearing of different gear ratios connecting said member and each of said transmitters.
10. In a correction device for gyro compasses for correcting the transmitted reading in accordance with the expression
- $$\frac{aK \cos H}{\cos L} + b \tan L,$$
- a following element, a coarse cam mounted thereon, a corrective member moved therefrom in accordance with the cosine of the course, a single means settable in accordance with both speed and the cosine of the latitude for varying the amount said member is moved from said cam, independent means settable in accordance with the tangent of the latitude for giving said member an additional corrective movement, and transmitting means driven by the combined movements of said element and member.

In testimony whereof I have affixed my signature.

JOSEPH L. CHANTEMERLE.
